DESIGN FOR A COMBINED LAWN FIGURE AND SIGN

Florence L. Kincannon, Palm Harbor, Fla.

Application March 22, 1943, Serial No. 109,784

Term of patent 14 years

To all whom it may concern:

Be it known that I, Mrs. Florence L. Kincannon, a citizen of the United States, residing at Palm Harbor, in the county of Pinellas and State of Florida, have invented a new, original, and ornamental Design for a Combined Lawn Figure and Sign, of which the following is a specification, reference being had to the accompanying drawing, forming part thereof.

In the drawing:

Fig. 1 is a front elevational view of a combined lawn figure and sign, showing my new design; and

Fig. 2 is a side elevational view thereof.

I claim:

The ornamental design for a combined lawn figure and sign, substantially as shown.

FLORENCE L. KINCANNON.
